Des. 200,686
Patented Mar. 23, 1965

200,686

KITCHEN MACHINE BASE OR THE LIKE

Walter Häuptli, Bruscholz, Aarburg, Switzerland, assignor to Rotel AG, Aarburg, Switzerland, a corporation of Switzerland

Filed Apr. 20, 1964, Ser. No. 79,609

Term of patent 7 years

(Cl. D89—1)

FIG. 1

The essential features of the design are shown in full lines.

I claim:

The ornamental design for a kitchen machine base or the like, substantially as shown and described.
